UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

POPGUN.

Application filed August 2, 1926. Serial No. 126,554.

The invention relates to guns and refers more particularly to pop guns of that type in which air is compressed by the movement of a spring-pressed plunger to eject a cork or stopper from the nozzle end of the barrel. The invention has among its objects the simplifying of the construction of the parts necessary to perform the required functions, the arranging of the parts so that they may be readily and quickly assembled and the reinforcing of the parts so that they will properly take care of the stresses to which they are subjected.

Other objects of the invention reside in the novel features of construction and combinations and arrangements of parts as more fully hereinafter set forth.

In the drawings:—

Figure 1 is a side elevation of a gun embodying my invention;

Figures 2 and 3 are vertical longitudinal sections through the gun;

Figure 4 is a side elevation of the plunger assembly;

Figure 5 is an enlarged section on the line 5—5 of Figure 4;

Figure 6 is a view similar to Figure 4 showing a modified construction.

The gun has the barrel 1 and the frame 2 which are formed from an integral sheet metal blank having a portion bent into cylindrical form with overlapping edge portions to form the barrel and wing portions terminating in inturned flanges to form the frame. The inturned flanges which form the bottom of the frame are cut away to provide an opening for the trigger which may be inserted by spreading apart the inturned flanges.

The plunger assembly comprises the plunger 3 which is insertable within the barrel 1 and has the shank 4 terminating at its rear end in the hook 5 formed by a transverse portion of the shank. 6 is a coil spring surrounding the shank and having its front end abutting the plunger and its rear end engageable over the tongue 7 and abutting the shoulders 8 upon the abutment member 9. This abutment member is formed of sheet metal and has the depending reinforcing flanges 10 extending longitudinally thereof at its sides. The top of the abutment member is formed with the longitudinally extending slot 11 for engagement by the hook 5 of the shank. The rear

end portion of the abutment member is inclined downwardly and rearwardly and terminates in the return bent portion 12. 13 is the trigger also formed of sheet metal and provided at its upper end with the hook 14 which is insertable through the aperture 15 formed in the top of the abutment member in rear of the slot 11. 16 is a coil spring having its front end telescoping over the projection 17 formed at the rear side of the trigger and its rear end abutting the return bent portion 12 of the abutment member. This coil spring normally holds the trigger in position so that the sear 18 is engagable by the hook 5 of the shank. 19 is a link which in the present instance is formed of a U-shaped wire. The link extends longitudinally at the top of the abutment member and the transverse portion 24 at the front end of the link is engageable with the hooks 5 of the shank to retract the shank and plunger to engage the hook with the trigger sear.

20 is the stock of the gun having the sheet metal U-shaped member 21 secured to its front end and adapted to engage over the frame 2 of the gun. 22 is a pivot insertable through aligned openings in the U-shaped member and the frame and also through the eye formed by the return bent portion 12 of the abutment member. 23 is a pin extending through the U-shaped member 21 and the eyes 24' formed at the rear of the link 19 for pulling this link rearwardly upon breaking the gun. The arrangement is such that the ends of the longitudinally extending slot in the abutment member are engaged with the hook of the plunger shank to limit the movement thereof in either direction. The front end of the slot limits the forward movement of the plunger and the rear end of the slot limits the rearward movement of the plunger and consequently limits the breaking down movement of the gun stock.

Also with the arrangement of parts it will be readily seen that the abutment member is reinforced by the longitudinally extending side flanges and furthermore has a strong construction of eye for attaching to the pin which connects the frame to the stock. It will also be seen that the construction of parts is such that they may be cheaply manufactured and readily assembled.

In the modified construction shown in Figure 6 the arrangement of parts is the

same with the exception of the eye formed at the rear end of the abutment member 25 for engagement by the pivot which connects the U-shaped member of the stock to the frame. This eye is formed by the return bent portion 26 at the rear end of the abutment member extending downwardly and forwardly and terminating in a tongue over which the rear end of the coil spring 27 telescopes. This arrangement also permits of cheap manufacture and ready assembly.

What I claim as my invention is:

1. In a gun, the combination with the barrel and frame, of a plunger assembly insertable within said barrel and frame and comprising a plunger having a hooked shank, a spring surrounding said shank and having one end abutting said plunger, a flanged abutment member for the opposite end of said spring having a slot for engagement by the hook of said shank, and a trigger carried by said abutment member and provided with a sear for engagement by the hook of said shank.
2. In a gun, the combination with the barrel and frame, of a plunger assembly insertable within said barrel and frame and comprising a plunger having a hooked shank, a spring surrounding said shank and having one end abutting said plunger, an abutment member for the opposite end of said spring having a longitudinally extending slot for engagement by the hook of said shank and longitudinally extending reinforcing flanges at the sides of the slot, a trigger carried by said abutment member and provided with a sear for engagement by the hook of said shank, and a spring between said trigger and abutment member.
3. In a gun, the combination with the barrel and frame, of a plunger assembly insertable within said barrel and frame and comprising a plunger having a hooked shank, a spring surrounding said shank and having one end abutting said plunger, an abutment member for the opposite end of said spring having a slot for engagement by the hook of said shank and a return bent portion at the rear end thereof and a trigger carried by said abutment member, a stock member and a pivot for attaching said stock member to said frame, said pivot extending through the return-bent portion of said abutment member.
4. In a gun, the combination with the barrel and frame, of a plunger assembly insertable within said barrel and frame and comprising a plunger having a hooked shank, a

spring surrounding said shank and having one end abutting said plunger, a flanged abutment member for the opposite end of said spring having a longitudinally extending slot for engagement by the hook of said shank, a return bent portion at its rear end, a trigger carried by said abutment member and provided with a sear for engagement by the hook of said shank, and a link extending longitudinally of said abutment member and adapted to actuate said shank, a stock member, a pivot for attaching said stock member to said frame, said pivot extending through the return bent portion of said abutment member, and a pin for attaching said link to said stock member.

5. In a gun, the combination with the barrel and frame, of a plunger within said barrel having a hooked shank, a spring surrounding said shank and having one end abutting said plunger, a sheet metal abutment member for the opposite end of said spring having a longitudinally extending slot in its top for engagement by the hook of said shank, said abutment member also having depending reinforcing flanges at its sides and a return bent portion at its rear end, a trigger carried by said abutment member and provided with a sear for engagement by the hook of said shank and a link extending longitudinally of said abutment member for actuating said shank, a stock member, a pivot for securing said stock member to said frame, said pivot extending through the return bent portion of said abutment member and a pin for securing said stock member to said link.

6. In a gun, the combination with the barrel and frame and a stock pivotally connected to said frame, of a plunger extending within said barrel and having a hooked shank, a spring having one end abutting said plunger within the abutment member for the opposite end of said spring having a slot for engagement by the hook of said shank with ends positioned to limit movement of said shank in opposite directions, a trigger carried by said abutment member and provided with a sear for engagement by the hook of said shank, and a connection between said stock and shank whereby breaking down movement of said stock moves the hook of said shank into engagement with said sear, the breaking down movement of said stock being limited by an end of the slot in said abutment member.

In testimony whereof I affix my signature.
CHARLES F. LEFEVER.
